UNITED STATES PATENT OFFICE.

GUY HILL, OF WASHINGTON, DISTRICT OF COLUMBIA.

COMBINED WAVE-CHANGER AND WAVE-METER.

1,338,984.

Specification of Letters Patent. Patented May 4, 1920.

Application filed October 7, 1918. Serial No. 257,182.

To all whom it may concern:

Be it known that I, GUY HILL, a citizen of the United States, and a resident of Washington, District of Columbia, have invented certain new and useful Improvements in Combined Wave-Changers and Wave-Meters, of which the following is a specification accompanied by drawings.

This invention relates to radio signaling apparatus, but more particularly to wave changing devices and the primary object of the invention is to provide operative means in connection with the wave changer for positively determining wave lengths. To this end the apparatus embodies a wave changer and wavemeter combined in a unitary structure having common means for simultaneously adjusting both the wave changer and the wavemeter.

In radio transmitting sets, such as arc sets, where coupled circuits are not employed, impact sets, and certain forms of two-audion sets where the radiated wave length depends upon the constants of the antenna circuit and not upon the constants of the primary circuit, the operator has no method of knowing the wave length transmitted after the set is once tuned and adjusted; in case the constants of the antenna are changed; that is, if the set was adjusted to a fixed antenna and this antenna became destroyed, and a new antenna of different constants had to be used, the operator could in no way determine the wave length being transmitted, unless he was provided with a wavemeter.

If such a set includes a wavemeter, which is a separate piece of apparatus, such an instrument might easily be removed from the set, and if the transmitting set were on ship-board the wavemeter could easily be left ashore, or in some inaccessible place, so that in case of emergency the operator might have no method of knowing the wave length he was using.

The present invention overcomes the above difficulties by having a wavemeter built into the transmitting set and forming an integral part of the transmitting equipment, and in addition so mechanically coupled to the transmitter that when the wave length is changed the wavemeter is also adjusted to prevent the operator setting his wave-changing switch on one wave length and his wavemeter on another, and thereby cause confusion.

The drawing is a diagrammatic representation of circuits and apparatus for carrying out the invention.

Referring to the drawing, A represents the antenna, connected in circuit with which is a loading coil system B having sections a, b, c and d, each provided with adjustable slider clips e connected to contact studs a', b', c' and d' on transmitter switch panel C.

A wave changing switch arm D connected to shaft E is adapted to sweep over and make successive contact with studs a', b', c' and d' for varying the loading inductance.

Arm D is connected to ground at E' through a suitable source of supply F of high frequency oscillations which may be an arc generator, and for the purposes of this invention, the source of supply F is merely indicated conventionally, it being understood that any other desired apparatus instead of an arc may be used. The invention may be applied to a quenched spark set, for instance, and the leads f and g shown in connection with the conventional device indicated by the letter F may lead to a primary circuit or to a source of supply of high frequency oscillations.

The wavemeter P, together with its controlling devices and connections, is preferably adapted to be built into the transmitting set and forms a part thereof and of the wave changer, so that the wave changer and wavemeter become an auxiliary unit. A single loop G is inserted in the antenna circuit and the wavemeter circuit includes a similar loop H, inductively coupled to loop G; an ammeter or indicating instrument J, a condenser K and an inductance L, provided with slider clips e connected to contact studs h, i, j and k respectively, on wavemeter panel M. A switch arm N carried by shaft E cooperates with contacts h, i, j and k for varying inductance L. A handle O on shaft E provides means for operating the meter switch N and transmitter inductance switch D simultaneously.

The drawing represents circuits and connections for four different wave lengths; for example, 300, 600, 900 and 1200 meters, on antenna A, beginning with the shortest wave length when arms D and N are on contacts a' and h respectively. The amount of inductance in loading coil section a for the shortest wave will be adjusted by its slider clip e and a similar adjustment is made on inductance L so that the wavemeter circuit

is in resonance for the desired wave length when the antenna circuit is accurately tuned to the same wave length.

After the set is once installed and the 5 wavemeter P calibrated, the operator has but one handle O for manipulation in making adjustments for change of wave length. The provision of common operative means between switches D and N prevents the operator through carelessness or in time of excitement, from setting his wave changing switch arm D on contact b' for, instance, and his wavemeter arm N on the wrong contact, as contact h , and then attempting to 10 tune the set by means of the wavemeter P, in which case he would believe he was sending on one wave length but might actually tune the set for a different wave length.

I claim and desire to obtain by Letters 20 Patent, the following:

1. In a radio transmitting set, a unitary structure for simultaneously changing and automatically measuring wave lengths, comprising in combination with an antenna and variable loading inductance, of a wavemeter 25 built into the said transmitting set and forming an integral part of the same, said wavemeter being coupled to the antenna and including a variable inductance, a wave changing switch for controlling the antenna loading inductance, a wavemeter switch for 30 controlling the variable wavemeter inductance, and common means for simultaneously actuating both said switches for adjusting

the loading inductance and the wavemeter 35 inductance whereby the wavemeter circuit is automatically brought into resonance for the desired wave length when the antenna is tuned to the same wave length.

2. In a radio transmitting set, a unitary 40 structure for simultaneously changing and automatically measuring wave lengths, comprising in combination with an antenna and variable loading inductance, of a wavemeter built into the said transmitting set and 45 forming an integral part of the same, said wavemeter being coupled to the antenna and including a variable inductance, adjustable contacts and contact studs for both the loading inductance and wavemeter inductance, 50 switches coöperating with the contact studs for controlling both of said variable inductances, and common means for simultaneously actuating both said switches for adjusting the loading inductance and the 55 wavemeter inductance, whereby the wavemeter circuit is automatically brought into resonance for the desired wave length when the antenna is tuned to the same wave length.

In testimony whereof I have signed this specification in the presence of two subscribing witnesses.

GUY HILL.
